UNITED STATES PATENT OFFICE.

LOUIS H. HIRSCH, OF NEW YORK, N. Y.

DESIGN FOR A FLOWER-VASE.

59,224.

Specification for Design.

Patented Oct. 4, 1921.

Application filed November 20, 1920. Serial No. 425,573. Term of patent 3½ years.

To all whom it may concern:

Be it known that I, LOUIS H. HIRSCH, a citizen of the United States, residing at New York city, in the county and State of New York, have invented a new, original, and ornamental Design for a Flower-Vase, of which the following is a specification, reference being had to the accompanying drawings, forming a part thereof, and in which:

Figure 1 is a side elevation, and

Fig. 2 a top view of a flower vase embodying my design.

I claim:

The ornamental design for a flower vase, as shown.

LOUIS H. HIRSCH.
